LAMP STAND

Edward C. Walker, Woodspeen, Forest Corner,
Ringwood, Hampshire, England

Filed June 17, 1969, Ser. No. 17,742

Claims priority, application Great Britain Mar. 10, 1969

Term of patent 14 years

Int. Cl. D26—02

U.S. Cl. D48—20

FIG. 1

FIG. 1 is a perspective view, taken from the rear, one side and above, of the lamp stand showing my new design;

FIG. 2 is an elevation of the opposite side thereof with the legs in a raised position; and

FIG. 3 is an end elevation thereof taken in the direction of the arrow 3 in FIG. 2.

I claim:

The ornamental design for a lamp stand, substantially as shown and described.
